UNITED STATES PATENT OFFICE.

HUGO SCHUBERT, OF NEW YORK, N. Y.

OVEN.

No. 902,175.

Specification of Letters Patent.

Patented Oct. 27, 1908.

Application filed May 24, 1907. Serial No. 375,515.

To all whom it may concern:

Be it known that I, HUGO SCHUBERT, a citizen of the United States, and a resident of New York, county of New York, and State of New York, have invented certain new and useful Improvements in Ovens, of which the following is a full, clear, and exact description.

This invention relates more particularly to a baker's oven.

The primary object of the invention is to provide simple and efficient means whereby an oven is provided in which the heat is evenly distributed, and in which the oven may be quickly cooled, or have its temperature quickly changed to adapt it for baking various kinds and classes of articles.

A further object of the invention is to provide means whereby the greatest efficiency is obtained by causing the products of combustion to circulate properly around and about the oven before passing to the chimney.

With these and other objects in view, the invention will be hereinafter more particularly described with reference to the accompanying drawings, which form a part of this specification, and will then be pointed out in the claims at the end of the description.

In the drawings, Figure 1 is a vertical section of one form of oven embodying my invention, taken on the line I—I of Fig. 2. Fig. 2 is a sectional plan taken on the line II—II of Fig. 1. Fig. 3 is a sectional plan through the oven taken on the line III—III of Fig. 1. Fig. 4 is a sectional plan taken on the line IV—IV of Fig. 1. Fig. 5 shows a slightly different way of supporting the beams of the air chamber; and Fig. 6 is a sectional plan taken on the line VI—VI of Fig. 1.

The oven is ordinarily constructed of brick or a combination of brick and other material, and may be of any desired shape. As shown the setting or casing 10 is provided with a suitable grate 11 over which is an arch 12 forming the usual furnace or furnace chamber. The furnace chamber has longitudinally extending side partitions 13, and in said partitions are openings 14 near the front part thereof through which pass the products of combustion to each side of the furnace to the chambers 15. These chambers have a side wall, deflector or partition 16, and at the rear of each of said partitions are openings 17 which form a communication between the chambers 15 and the chambers

18. One or more flues 19 are arranged at the rear of the furnace through which some of the products of combustion pass, and at the front portion of the chamber 18 are the flues 20, shown in dotted lines Fig. 2 and full lines Fig. 3, through which most of the products of combustion from the furnace pass after passing through the chambers 15 and 18, and from there pass into the heating chamber 21 arranged over the oven proper or baking chamber 22. By this means the products of combustion are made to take a circuitous route through the various chambers before passing into the heating chamber 21.

An air chamber 23 is arranged beneath the oven or baking chamber 22, and over the furnace and the chambers 15 and 18. The chambers 15 and 18 each have an arch of brick or other material, and said air chamber 23 is formed by a series of arches which rest upon the flange of the I-beams 24. These I-beams 24 are set in concrete 25, and over the concrete is a layer of sand 26, and above the sand are the tiles 27 forming the base of the oven proper 22, though instead of the I-beams being supported as shown, the partitions 13 of the furnace may be extended so that the beams will rest thereon as shown in Fig. 5.

The upper part of the oven or baking chamber 22 is arched, as at 28, and forms the lower surface of the heating chamber 21. This chamber 21 has a series of partitions or deflectors as best shown in Figs. 1 and 4 to 90 cause the products of combustion to pass alternately from front to rear of said chamber so that the latter will be evenly heated throughout its entire surface. The products of combustion from the flues 20 pass upward on the outside of the oven 22 and enter the chamber 21 at the front ends thereof. This chamber 21 is provided with a plurality of deflectors or partitions 29, each of which has an opening 30 which alternate with respect to each other, so as to cause the products of combustion to pass from the front to the rear and then to the front again and so on to the central part thereof. At this point there is a partition 30^a, forming independent compartments, and on each side of the partition at the front thereof is a flue 31 in each of which is arranged a damper 32. The dampers 32 are arranged to control the exit of the products of combustion from the chamber 21 so as to regulate its passage to the chimney flue 33, which may be located at any convenient

point so as to connect with the usual chimney. The flues 19 at the rear open into the central chambers 34 and 35, by which a part of the products of combustion may pass direct to the chimney flue 33. By closing either of the dampers 32, the oven or baking chamber 22 may be heated on one side only, or throughout its entire surface as desired.

For the purpose of cooling the baking chamber so as to obtain quickly different degrees of temperature to adapt the oven to bake different articles requiring different degrees of heat, I arrange at the rear of the baking chamber one or more flues 36. These flues 36 may be of any suitable shape and may be located at any desired point, and said flues may connect in any suitable way with the chimney flue and are each provided with a damper 37 by which the said flues may be opened or closed as desired. These dampers are provided with a rod which may be operated from the front of the oven setting so that by opening said dampers the baking chamber may be quickly cooled, and by closing the same the heat may be properly retained within the chamber.

It will be understood that where the heat comes in contact with the setting, the same may be lined with fire-brick for the purpose of making the oven and parts more lasting, and it will be further understood that the exact arrangement and the position of the partitions and flues may be changed without departing from the character of the invention.

From the foregoing it will be seen that simple and efficient means are provided whereby the heat from the furnace may be caused to pass throughout the entire length and width of the baking chamber, and from there is caused to pass by a circuitous route over the entire upper surface of said chamber before passing to the chimney flue, and that said baking chamber may have its temperature regulated to exactness and may have its temperature changed for the purpose of permitting various articles to be baked therein.

Having thus described my invention, I claim as new and desire to secure by Letters Patent:—

50 1. In a baker's oven, the combination with a setting having a furnace chamber, of an air chamber over the furnace chamber, a heating chamber having independent compartments separated by a central partition, a 55 baking chamber between the air chamber and the heating chamber, chambers arranged along the furnace chamber at the side thereof, a plurality of partitions arranged in the heating chamber on each side of the longitudinal center and having openings arranged alternately so as to cause the heat to pass from the front to the rear and vice versa, a 60 plurality of flues leading from the baking chamber to cool the same at each side of the 65 longitudinal center thereof, means for con-

trolling each oven flue independent of the other, flues connecting the chambers at the side of the furnace chamber and the heating chamber, and flues connecting the furnace chamber with the heating chamber at the front and rear thereof, whereby the products of combustion is made to pass to the front and to the rear of the heating chamber to distribute the heating evenly over the baking chamber.

2. In a baker's oven, the combination with a setting having a furnace chamber extending the length of the oven and a plurality of chambers arranged on each side thereof and communicating with the furnace chamber, of a baking chamber located above the furnace, a closed air chamber arranged between the baking chamber and the furnace, a heating chamber having a plurality of partitions arranged on each side of the longitudinal center and provided with openings alternately arranged to cause the products of combustion to pass from the front to the rear and vice versa toward the center so as to heat the entire surface of the baking oven, a central partition extending throughout the length of the heating chamber and dividing said heating chamber into independent compartments, a chimney flue, independent flues connecting the furnace chamber and the chambers at the side of the furnace chamber with the heating chamber at the front and rear thereof, a plurality of flues connecting the baking chamber with the chimney flue at each side of the longitudinal center, dampers for regulating the passage of the products of combustion into the chimney flues, and dampers in the flues leading from the baking chamber, whereby the products of combustion is made to pass to the front and to the rear of the heating chamber to distribute the heating evenly for the baking chamber.

3. In a baker's oven, the combination with a setting having a furnace chamber extending the length of the oven, and a plurality of chambers arranged at each side thereof and provided with openings alternately arranged and communicating with the furnace chamber to cause the products of combustion to pass from the front to the rear and back to the front again, of a baking chamber located above the furnace chamber and having the rear end thereof closed, a closed air chamber arranged between the baking chamber and the furnace chamber, a heating chamber having a number of partitions arranged on each side of the longitudinal center of said chamber and provided with openings alternately arranged to cause the products of combustion to pass from the front to the rear and vice versa toward the center so as to heat the entire surface of the baking oven, a central partition extending throughout the length of the heating chamber and dividing

said heating chamber into independent compartments, a chimney flue communicating with the compartments on each side of the vertical partition of the heating chamber independent of each other, independent dampers controlling the exit of the products of combustion from the heating chamber on each side of the said partition and entirely independent of each other, independent flues 5 connecting the outer chambers located adjacent to the furnace chamber at their forward ends with the outer compartments of the heating chamber, independent flues arranged at the rear of the furnace chamber 10 and communicating with the rear of the heating chamber whereby the products of combustion from the furnace chamber may 15

pass both from the rear and front to the rear and front of the heating chamber to properly distribute the heat throughout the entire surface of the heating chamber, a plurality of flues connecting the baking chamber with the chimney flue at each side of the longitudinal center, and dampers for closing or opening either or both of the flues from the baking chamber whereby different degrees of heat may be obtained in the baking chamber. 20 25

This specification signed and witnessed this 22d day of May A. D. 1907.

HUGO SCHUBERT.
